UNITED STATES PATENT OFFICE.

P. HENRY GRIFFIN, OF DETROIT, MICHIGAN.

METALLIC CURBING FOR CONTAINING ELECTRICAL WIRES.

SPECIFICATION forming part of Letters Patent No. 310,271, dated January 6, 1885.

Application filed September 10, 1884. (No model.)

To all whom it may concern:

Be it known that I, P. HENRY GRIFFIN, of Detroit, in the county of Wayne and State of Michigan, have invented new and useful Improvements in Metallic Curbings for Containing Electrical Wires; and I do hereby declare that the following is a full, clear, and exact description thereof, reference being had to the accompanying drawings, which form a part of this specification.

This invention relates to certain new and useful improvements in the construction of metallic curbs of that class designed to be substituted for the ordinary stone curbings used at the sides of streets, and adapted to perform the double office of curbing and of concealing within itself telephone, telegraph, and all wires for electric purposes.

It is well known that many municipalities have passed ordinances requiring electric wires for all purposes to be removed from the poles upon which they are ordinarily suspended, and carried under ground, and it has been the subject of much speculation, experiment, and inventive skill to determine in what manner this may be done with the most economical results.

To carry out the spirit of such ordinances, if not the exact letter, is the object of this invention, which consists in the peculiar combinations and the construction and arrangement of parts hereinafter more fully described and claimed.

Figure 1 shows a section of a paved street with my improved curbing in place. Fig. 2 is a perspective view of a single section of such curbing. Fig. 3 is a vertical cross-section of the same.

In the accompanying drawings, which form a part of this specification, A represents a cast-iron box, made of suitable size and shape to take the place of the curbstone at the edge of the pavement. This box is open at both ends, and is provided with a removable top or slide, B, which is provided with depending flanges a to hold it in place. In addition to this box performing the office of a curbstone, it is designed for the purpose of holding all kinds of electric wires, which are properly insulated, and which may be inclosed in pipes of lead or iron, or laid upon suitable racks in the box when a large number of wires are used.

It will readily be seen that such a box-curb-ing will provide a receptacle for the wires, so that in case of necessity of repairs the wires could always be got at without disturbing the pavement of the street or sidewalk, or digging up the earth. As pavements are always laid upon a grade sufficient to carry off the water of the surface, the curbing is laid always upon the same grade, and some means are usually employed at street-corners by which the gutters connect with underground sewers which receive the surface-water, so that should the box-curb-ing from any cause be filled or partially filled with water it is so arranged as to discharge such water into the sewer-openings; but where such underground sewers are not provided I connect the box-curb-ing with a well, C, into which the water may drip from the curbing, and from whence it may be pumped out, if required. Where it is desired to make this curbing-box so that water will not enter it between the ends of the section, it should be cast upon the same plan as water-pipes, with one end enlarged to embrace the adjacent end of its fellow section, and when laid packing of any suitable character is inserted between the joints thus made; or they may be cast with lugs at each end, so that the sections can be bolted together with packing between the ends thereof. At points where streets intersect it would be necessary to run the curbing-boxes under the pavement at such intersections; but the principal aim I have in view is to provide a means whereby the tearing up of streets to lay the pipe and other appliances of this nature could be dispensed with in a large measure, and where eighty or ninety per cent. of the receptacles for the wires would be at all times accessible when repairs become necessary to the inclosed wires. The preferable way, the curbing being laid as described, would be to insert the insulated wires (as many as necessary) in lead pipes, which may be done at the factory, ready to lay, as such pipes are uncoiled, into the hollow curbs, drawing the end thereof through the hollow curb when the same is laid under the street at intersections.

I am aware of the Patent No. 249,400, and make no claim to the construction shown therein as forming part of my invention.

I am also aware of the Patents Nos. 235,611

and 284,655, and make no claim to the constructions shown therein as forming part of my invention.

What I claim as my invention is—

- 5 1. The metallic curbing herein described, consisting of the metallic box A, having two substantially vertical sides, a closed bottom, and an open top, with an opening, a', at the junction of one of the sides with the bottom, and provided with a removable top having depending flanges a, substantially as described.
- 10 2. The metallic curbing herein described,

consisting of the open box A, having two vertical sides, an open enlarged end, a removable top, and an opening, as a', formed at the junetion of the bottom with one of the sides for the passage of water, in combination with the well C, to receive the discharge, all constructed and arranged substantially as shown and described.

P. HENRY GRIFFIN.
